JOSEPH T. MENGEL, OF KNOXVILLE, TENNESSEE

VENEER-CUTTING MACHINE

Application filed December 31, 1927. Serial No. 244,007.

This invention relates to machines for cutting veneer from logs or blocks or sections of wood, the machine comprising a knife which is adapted to cut from the face of the wood a thin sheet or layer of wood while the piece of wood and the knife are moved relative to each other, the knife bearing on the surface of the wood.

The object of this invention is to produce a machine which is adapted to cut the wood along a sinuous or wavy line, the variations from a straight line being sufficient to cause parts of the cutting to be in or through one fiber layer of the wood while other portions of the cutting are in another layer or layers of the wood fiber, such cutting resulting in a veneer sheet which is corrugated or wavy or sinuous in transverse section and which has a greater variety of surface appearance than is possessed by the surface of a veneer sheet cut by means of a knife having its cutting edge in a straight line. Furthermore, the veneer sheet cut by a knife having the sinuous cutting edge cuts through the wood fiber at different angles. Thereby different parts of the face of the veneer sheet absorb in different proportions or quantities oils, stains, shellacs, and varnishes and other materials used for "finishing" the face of the veneer sheet. This variation in absorption is another factor in giving to the veneer sheet a variety of appearance.

My invention relates particularly to the form of the knife and the form of the pressure bar which cooperate in the cutting and the discharge of the veneer.

In the accompanying drawings,

Fig. 1 illustrates a cross section of a veneer cutting machine or lathe embodying my improvement;

Fig. 2 is a perspective showing a part of the knife and a part of the pressure bar positioned in relation to each other;

Fig. 3 is a perspective view of a part of the knife showing the sinuous cutting edge;

Fig. 4 is an upright section on the line, 4-4, of Fig. 3, looking in the direction of the arrow;

Fig. 5 is a similar section on the line, 5-5,

of Fig. 3, looking in the direction of the arrow;

Fig. 6 is a horizontal section on the line, 6-6, of Fig. 5;

Fig. 7 illustrates one face of a part of a veneer sheet cut by my improved machine.

Machines for cutting veneer by means of a knife and a pressure bar are well known in this art. Hence it is considered unnecessary to fully illustrate and describe such a machine.

Fig. 1 is a transverse upright section of such a machine adapted to cutting a veneer sheet from a log, the log being rotated, as is now done in similar machines and the cutting knife and the pressure bar being stationary.

In the drawings, A is a lower, horizontal, stationary frame member, and C is an upper, horizontal stationary frame member. The frame member, A, supports the knife and the frame member, C, supports the pressure bar. These two frame members have their ends immovably supported by the ends of the general structure of the machine, as is already well known in this art. The member, A, has an approximately upright flange, A¹, which has a plane face directed toward the log, L. On said face is a lug or bracket, A², integral with the member, A. The cutting knife, B, is placed against said plane face above the lug, A². Any desired number of lugs, A², are to be placed on the flange, A¹, below the knife.

A bolt, A⁵, is threaded upward through the lug, A², and made to bear against the lower edge of the knife. By turning said bolt so as to vary its height, the height of the knife may be adjusted. A bolt, A⁶, extends through a slot, B⁴, (Fig. 2) and is threaded into the frame member, A. A nut, A⁷, surrounds the outer part of said bolt and is to be driven toward the member, A, for binding the knife against said member when the knife has been adjusted to the desired height by means of the bolt, A⁵. Any number of such bolts, A⁶, and slots, B⁴, are to be used. This manner of supporting and binding the knife on the frame member, A, is old.

The frame member, C, has a horizontal flange, C¹, and an upper flange, C², which

extends upward and toward the right so as to stand in a plane which forms an acute angle with the plane of the flange, C¹. The frame member, C, is so positioned as to bring the intersection of those planes close to the edge of the cutting knife, B. At the junction of those planes, the member, C², is channeled to form a space to receive the pressure bar, D, said bar resting against a horizontal downward-directed face, C³, and extending downward a little below the adjacent part of the lower face of the member, C. From the pressure bar toward the free edge of the flange, C¹, the lower face of the member, C, is cut away far enough to receive the clamping plate, C⁴. In cutting away to make room for this plate, a shoulder, C⁵, is formed on the member, C, which constitutes an abutment for the adjacent edge of the clamping plate. Said plate overlaps a part of the pressure bar, D. Since the pressure bar extends a little below the adjacent face of the member, C, the overlapping part of the clamping plate bears against the pressure bar and not against the adjacent part of the adjacent face of the member, C. Adjacent the shoulder, C⁵, the clamping plate bears against said bar. A bolt, C⁶, extends obliquely upward through the clamping plate and the adjacent part of the frame member, C, and serves to bind the clamping plate against the pressure bar and against the frame member, C.

To adjust the pressure bar, D, a bolt, C⁷, is threaded obliquely through the body of the frame member and made to bear against the adjacent back face of the pressure bar. When the bolt, C⁷, has been slightly loosened, the bolt, C⁶, may be turned to drive the pressure bar toward the knife, B, or the bolt, C⁷, may be retracted and the pressure bar moved away from the knife, B. After such adjustment, the bolt, C⁶, is to be again made tight.

The face of the knife, B, which rests against the upright face of the frame member, A, is in a plane which slightly cuts the log and which is close to the working edge of the pressure bar. The opposite side of the knife, B, is beveled so as to rest near the adjacent part of the face of the log, L.

If the cutting edge of the knife, B, were straight and in the plane of the adjacent face of the frame member, A, or parallel to or near that plane, the knife would cut a straight sheet of veneer from the rotating log; and such cutting would be approximately parallel to the fiber layers in the log, and the veneer sheet would be flat and not sinuous or wavy.

Figs. 2 to 6, inclusive, show the form of the cutting knife whereby the knife is adapted to cut the veneer sheet in wavy or sinuous form and in different fiber layers.

In forming this cutting knife, a steel plate of appropriate thickness and length and which is used. For the purpose of explanation, it is assumed that the upper edge of

the plate is straight and flat and in a plane which is perpendicular to the body of said plate.

In Figs. 3, 4 and 5, the beveled face of the cutting knife is shown turned toward the right. In Fig. 2, it is shown toward the front or left. To illustrate the manner of developing the sinuous or wavy cutting edge, let it be assumed that alternate portions of the upper part of that face are made slanting toward the opposite face of the knife a distance equalling the distance at which parts of the cutting edge, B⁸, are to stand from the plane of the straight face of the knife. And let it be assumed that the beveled face of the cutting knife is similarly cut on sections alternating the cut sections of the opposite face of the knife, this cutting on the beveled face being only enough to form a cutting edge, the metal being allowed to remain in the plane of the upper edge of the bar from which the knife is formed, said plane being perpendicular to the body of the knife.

These cuttings at each side of the knife are to be so curved as to make the cutting edge sinuous or wave form, the deviation from a straight line being only as much as will cause such difference in depth of cutting into the wood surface as will present on the veneer surface the desired fiber variation.

The function of the pressure bar, D, is to press upon and to some degree condense the log surface immediately above the cutting edge of the knife, B. The approximately upright or side face of the pressure bar is made wavy to conform to the waves or sinuositites in the upright face of the knife, B, in order that the gap or passage between the pressure bar and the cutting edge of the knife may be uniform, and in order that the pressure by the pressure bar upon the wood may be approximately uniform on all parts of the sheet passing from the log. In other words, the pressure bar is to present an edge which is parallel to the sinuous knife edge.

To attain that parallelism, the lower face of the pressure bar is also to be made sinuous to such extent as may be necessary when the pressure bar is in a plane which is at an angle of less than ninety degrees to the plane of the adjacent face of the cutting knife, B. The cutting edge of the knife being in a horizontal plane, and the pressure bar being inclined, as above described, the above-mentioned parallelism can be attained only by also making the lower face of the pressure bar sinuous.

But the plane of the knife edge and the inclination of the pressure bar may be so related to each other as to allow making only the upright face of the pressure bar sinuous to create the parallelism above described.

It is to be noted that as soon as a cut has been made around the log, the log will have

a sinuous surface conforming to the sinuosities of the pressure bar. Then all parts of the pressure bar edge will bear on the wood.

5 The veneer sheet, V, issuing from the edges of the knife, B, and the pressure bar, D, moves away between the upper frame member, C, and the lower frame member, A. Said sheet may descend from the position shown in Fig. 10 1 and slide on any number of supports, A⁷, seated on the outer edge, A⁶, of the frame member, A.

I claim as my invention:

1. In a veneer cutting machine, the combination of a knife having a sinuous cutting edge, a pressure bar having a sinuous edge conforming to the cutting edge of the knife, means for supporting the knife and the pressure bar in relation to each other, and means 15 for supporting a body of wood, said means and the knife and pressure bar supporting means being adapted to impart relative movement.

2. In a veneer cutting machine, the combination of a knife having a sinuous cutting edge, a pressure bar having two sinuous faces forming an edge parallel to said cutting edge of the knife, means for supporting the knife and the pressure bar in relation to each other, and means for supporting a body of wood, said means and the knife and pressure bar supporting means being adapted to impart relative movement.

3. In a veneer cutting machine, the combination of a flat-faced knife body having a sinuous cutting edge in a plane perpendicular to the knife body, a pressure bar having a sinuous edge conforming to the cutting edge of the knife, means for supporting the knife and the pressure bar in relation to each other, and means for supporting a body of wood, said means and the knife and pressure bar supporting means being adapted to impart relative movement.

4. In a veneer cutting machine, the combination of a flat-faced knife body the upper part of which has its sides grooved alternately to form a sinuous knife edge, a pressure bar having a sinuous edge conforming to the cutting edge of the knife, means for supporting the knife and the pressure bar in relation to each other, and means for supporting a body of wood, said means and the knife and pressure bar supporting means being adapted to impart relative movement.

5. In a veneer cutting machine, the combination of a flat-faced knife body the upper part of which has its sides grooved alternately to form a sinuous knife edge in a plane perpendicular to the knife body, a pressure bar having a sinuous edge conforming to the cutting edge of the knife, means for supporting the knife and the pressure bar in relation to each other, and means for supporting a body of wood, said means and the knife and

pressure bar supporting means being adapted to impart relative movement.

6. In a veneer cutting machine, the combination of a flat-faced knife body having a sinuous cutting edge in a plane perpendicular to the knife body, a pressure bar in a plane forming an angle less than ninety degrees to the plane of the knife body and having two meeting sinuous faces forming a sinuous edge parallel to said knife edge. 70

7. In a veneer cutting machine, the combination of a knife having a sinuous cutting edge extending to a plane transverse to the body of the knife, and a pressure bar having an inclined face directed toward the position for the log and the lower part of said inclined face being near the cutting edge of the knife and having an edge which is sinuous to conform to the sinuosities of the knife. 75

8. In a veneer cutting machine, the combination of a knife having a sinuous cutting edge extending to a plane transverse to the body of the knife, and a pressure bar having an inclined face directed toward the position for the log and said pressure bar having a lower face meeting said inclined face near the cutting edge of the knife and said inclined face and said lower face being sinuous and forming a sinuous edge at their junction the sinuosities of which edge conform to the sinuosities of the cutting edge of the knife. 85

9. In a veneer cutting machine, the combination of a knife having a flat body and having a sinuous cutting edge in a plane approximately perpendicular to the body of the knife, a pressure bar having a sinuous edge conforming to the cutting edge of the knife, means for supporting the knife and the pressure bar in relation to each other, and means for supporting a body of wood, said means and the knife and pressure bar supporting means being adapted to impart relative movement. 100

In testimony whereof I have signed my name, this 21st day of December, in the year 110 one thousand nine hundred and twenty-seven.

JOSEPH T. MENGELE.
